UNITED STATES PATENT OFFICE.

ARTHUR SOWDEN, OF SHIPLEY, NEAR BRADFORD, ENGLAND.

WOOL AND OTHER FIBER DRYING MACHINE.

1,032,713.

Specification of Letters Patent. Patented July 16, 1912.

Application filed November 14, 1911. Serial No. 660,197.

To all whom it may concern:

Be it known that I, ARTHUR SOWDEN, a subject of the King of Great Britain, residing at Staveley Grange, Shipley, near Bradford, in the county of York, England, have invented certain new and useful Improvements in Wool and other Fiber Drying Machines, of which the following is a specification.

This invention relates to drying machines or apparatus employed for drying wool and other fibers and the like and to that type of apparatus in which the fiber to be treated passes over and under a number of revolving cylinders situated above steam pipes and revolving fans, the machine or apparatus being specially designed for use in combination with a back washing machine, or as an intermediate machine, or apparatus between a back washing machine and a gill box, the chief objects being to improve the construction of the drying cylinders and the arrangement of the heating appliances used in connection therewith and in the drying chamber, and also to provide an improved form of beater for shaking or agitating the fiber preparatory to the entrance of the latter to the drying chamber.

According to this invention the fiber or sliver enters the top of the drying chamber and is traversed the length thereof above the revolving cylinders and returned over a guide roller to the entrance end of the machine from whence it passes over and under the various revolving drying cylinders, each of which contains a fan. From the last of these cylinders the sliver passes over a series of fans and heating pipes to the front end of the machine and between such fans and heating pipes and another series of fans and heating pipes to the rear or delivery end of the machine.

A feature of the invention consists in interposing a heating pipe about the center of each group of three cylinders so that the fiber or sliver is heated on both sides at the parts where it leaves one cylinder to pass on to the next one. The feature of the invention relating to the drying cylinders consists in forming the latter with a perforated wall arranged or provided with means whereby an air space exists between the greater portion of the cylinder wall and the surrounding fiber or sliver with the result that air is forced through the perforations uniformly all around the cylinder by the

usual internal fans and issues through the perforations in a practically radial direction ultimately filling the spaces between the cylinder and the sliver, and causing the latter to be subjected to the heated air from within the cylinder and also to the heated air around the extension thereof.

The beater hereinbefore referred to comprises a rocking bar or member arranged to contact with the sliver at each of its ends and to beat the sliver twice for each reciprocation of the bar or member.

In the accompanying drawings:—Figure 1 is a vertical section of a machine constructed in accordance with this invention. Fig. 2 is a detached view showing a cylinder constructed in accordance with this invention and an old type of cylinder. Fig. 3 is a longitudinal section taken through a cylinder constructed in accordance with this invention showing the mechanism for driving the internal fans and, Fig. 4 is an elevation showing a slightly modified construction of cylinder.

A indicates the drying chamber, B the fiber or sliver, C the revolving drying cylinders and D the fans therein, E the fans and F the heating pipes situated below the revolving cylinders, G the heating pipes situated about the center of each group of three cylinders, and H the beater situated at or about the entrance end of the drying chamber.

In the example shown the latter contains five drying cylinders C each of which contains one of the aforesaid fans D as is usual. The beater H is double acting and comprises a frame *h* pivoted at *h*¹ and terminating at its opposite ends in cross bars *h*² which extend across the underside of the sliver. The frame *h* is connected at *h*³ with an eccentric rod *h*⁴ terminating in an eccentric *h*⁵ which receives motion from spur wheels *d*, *d*¹, of which the wheel *d*¹ is rigidly connected with a sleeve *d*² which carries the fan D appertaining to the first drying cylinder C. Vibration of the frame *h* due to the connections aforesaid, causes the cross bar *h*² to knock or tap the slivers or fiber thereby tending to open the same. The fiber or sliver B after leaving the beater H passes over a guide roller *b* situated in proximity to the entrance end of the machine and over similar guide rollers *b*¹, *b*², *b*³, and from the latter under and over the various heating cylinders to the guide roller *b*⁴ and from the

latter over and between two rows of fans E and heating pipes F to the rollers b⁵, b⁶ situated outside the delivery end of the machine.

- 5 The heating pipes G placed about the center of each group of three drying cylinders are curved at their upper and lower surfaces to follow the curvature of the cylinder and the sides of the heating pipes converge 10 toward the aforesaid lower surface so as to occupy a practically parallel position in relation to the adjacent portions of the sliver. These heating pipes act to a certain extent as baffle plates for directing the heated air 15 driven by the fan from the cylinder against the portions of the sliver which intervene between an upper and a lower cylinder and cause the sliver to be uniformly heated on both sides.
- 20 The perforated drying cylinders hereinbefore referred to are as already mentioned constructed or arranged in such a manner that a number of free air spaces exist between the outer wall of the cylinder and the 25 inner or adjacent surface of the fibers or slivers that are carried thereby. This may be effected in various ways, for example the cylinder C shown in the lower part of Fig. 2, and in longitudinal section in Fig. 3 comprises a sheet metal cylinder corrugated circumferentially as shown at c and formed with perforations c¹ both in the raised and in the recessed portion of the corrugations, bars or rods c² extending transversely across 30 the raised portions of the corrugations to support the fibers or slivers. In an alternative arrangement the cylinders C may be constructed from wire gauze c³ (Fig. 4) provided at intervals with rods or bars such 35 as c² to carry the fibers or slivers and to form the aforesaid air spaces between the outer walls of the cylinder and the adjacent inner portions of the slivers. By the arrangements above described there is a free 40 passage way for the hot air between the perforated walls of the cylinders and the inner surfaces of the fiber or sliver with the result that the latter are more readily opened out and are dried more quickly and 45 produce a better finish when dried. The drying cylinder C² shown above the corrugated cylinder in Fig. 2 is of the ordinary or well known type and comprises longitudinally spaced bars c⁴ connected with end frames c⁵. 50 This arrangement however is open to the objection that the greater portion of the air current set up within the cylinder by the fan D is expelled through that part of the cylinder which is not covered by the fibers or slivers and is not blown through the latter.

In carrying out this invention, the machine can be provided with the novel cylinders C exclusively, or, as shown in Fig. 1, other forms of cylinder may be used in combination with the novel form of cylinder,

and the non-revolvble pipes G may be used between each group of three cylinders irrespective of the specific construction of each cylinder. In this manner the novel cylinder can be added to existing machines when any 70 one of its cylinders becomes worn out or broken, and an entirely new machine does not have to be provided. The beater H may also be used irrespective of the specific construction of the drying cylinders inside the 75 machine. The fans D are conveniently driven by the spur wheels d, d¹ appertaining to each fan and previously referred to, these spur wheels being in turn driven by belts d² mounted upon pulleys d⁴ fixed on the 80 shafts d⁵ which carry the spur wheels d. The cylinders C are provided as usual, with teeth c⁶ the teeth on a lower cylinder gearing with the teeth upon an upper cylinder throughout the series, any suitable means 85 being provided for imparting motion to one or more of the cylinders.

What I claim as my invention and desire to secure by Letters Patent of the United States is:—

- 90 1. In a drying machine, the combination, with a series of revoluble drying cylinders arranged in a group about a common axis, of a non-revolvble heating pipe arranged substantially at the axis of the said group. 95
 2. In a drying machine, the combination, with a series of revoluble drying cylinders arranged in a group about a common axis, of a non-revolvble heating pipe arranged substantially at the axis of the said group, 100 and having a side portion which is substantially concentric with one of the said cylinders.
 3. In a drying machine, the combination, with drying cylinders, and a heating pipe 105 arranged between them; of means for guiding the material onto the said cylinders, and a beater arranged at the feed end of the machine and operating on the material to be dried.
 4. In a drying machine, the combination, with drying cylinders, and a heating pipe arranged between them; of means for guiding the material onto the said cylinders, and a double-acting beater arranged at the feed 110 end of the machine and operating on the material to be dried.
 5. In a cylinder drying machine, a double acting beater comprising a pivoted frame having a cross bar at each end for engagement with the material to be dried and means for imparting an oscillatory motion to such bar.
 6. In a drying machine, a drying cylinder formed of reticular material, and provided with a series of crossbars arranged around its periphery and operating to support the material clear of its reticular surface.
 7. In a drying machine, a drying cylinder 115 formed of reticular material and provided

with a series of corrugations, and having a series of crossbars arranged around its periphery and operating to support the material clear of its reticular surface.

5 8. In a cylinder drying machine, a corrugated drying cylinder having perforations formed in the outer recessed portions of the corrugations.

9. In a cylinder drying machine, a perforated drying cylinder formed with circum-

ferential corrugations and provided with cross pieces extending across the said corrugations to support the material to be dried.

In testimony whereof I affix my signature in the presence of two witnesses.

ARTHUR SOWDEN.
